(57) **CLAIM**

The ornamental design for a male pin holder for lighting fixture, as shown and described.

DESCRIPTION

FIG. 1 is a perspective view of a male pin holder for lighting fixture showing my new design therefor;

FIG. 2 is a left side elevational view thereof;

FIG. 3 is right side elevational view thereof;

FIG. 4 is front elevational view thereof;

FIG. 5 is rear elevational view thereof;

FIG. 6 is top plan view thereof; and,

FIG. 7 is bottom plan view thereof.

The male pin holder of the present invention is meant for use in a housing for a lamp head used in a lighting fixture.
